F. AND J. GLASS.

SANITARY CUSPIDOR.

APPLICATION FILED JUNE 21, 1919.

1,315,717.

Patented Sept. 9, 1919.

UNITED STATES PATENT OFFICE.

FREDERICK GLASS AND JOHN GLASS, OF GULFPORT, MISSISSIPPI.

SANITARY CUSPIDOR.

1,315,717.

Specification of Letters Patent.

Patented Sept. 9, 1919.

Application filed June 21, 1919. Serial No. 305,830.

To all whom it may concern:

Be it known that we, FREDERICK GLASS and JOHN GLASS, citizens of the United States, residing at Gulfport, in the county 5 of Harrison and State of Mississippi, have invented certain new and useful Improvements in Sanitary Cuspidors; and we do hereby declare the following to be a full, clear, and exact description of the invention, such as will enable others skilled in the art to which it appertains to make and 10 use the same.

The present invention relates to improvements in sanitary cuspidors, and has for an 15 object to locate a cuspidor out of sight beneath the floor with a cover forming a continuation of the floor for closing and concealing the cuspidor but arranged to be opened by the foot to disclose and give 20 access to the hidden cuspidor.

The invention will be found particularly useful in offices and railway cars.

In the accompanying drawings forming a part of this application, and in which similar reference symbols indicate corresponding parts in the several views:

Figure 1 is a vertical section through a floor, showing a sanitary cuspidor constructed in accordance with the present invention and with the cover in the closed position.

Fig. 2 is a similar view with the cover open.

Fig. 3 is a top plan view, with parts 35 broken away, of the same; and

Fig. 4 is a cross sectional view taken on the line 4—4 in Fig. 1.

Referring more particularly to the drawings, 1 designates a floor of a building, railway car, or the like, in which is made an opening 2 having a shoulder 3. A cuspidor 4 is placed beneath the opening 2 in the floor and, where the device is used in buildings, as for instances offices the lower 45 smaller end of the cuspidor 4 may be connected to a drain pipe or other outlet; whereas when used on railway cars the bottom of the cuspidor 4 may be left open.

The cuspidor is shown in Fig. 1 to be 50 normally concealed by a cover 5 forming a continuation of the floor 1, hinged to the floor as indicated at 6, and adapted to seat against the shoulder 3. The cover 5 is recessed on its under side, as indicated at 7, 55 to receive and form a close fit with the upper mouth of the cuspidor 4.

Near the hinge 6 the door is furnished with a bar 8 having pivotal attachment to the upper end of a link 9 which is pivoted at its lower end to a lever 10. The lever 10 60 is fulcrumed between its ends as at 11 on a stirrup or hanger 12, and at the other side of the pivot point 11 is connected to a pedal 13 which passes up freely through an opening 14 in the floor, so as to be depressed by the foot. A coil spring 15 is interposed between the lever 10 and the bottom of the floor 1.

Beneath one end of the lever 10 is a bracket 16 which receives the cross bar 17 70 of a second U-shaped lever 18 which straddles the cuspidor 4, and extends to the other side of the same. The U-shaped configuration of this lever 18 can be clearly seen by reference to Fig. 3. The two arms of the 75 U-shaped lever 18 are pivoted in the lower ends of a pair of hangers 19, depending from the floor 1, and to the other side of the lever pivotal point the arms of the lever are joined by a second cross bar 20 to the 80 central part of which is attached a pedal 21 having a vertically sliding movement through an opening 22 made in the floor 1.

In use, the device is normally in the position shown in Fig. 1, where the cover 5 is in 85 the horizontal position covering the opening 2 and mouth of the cuspidor 4, and lying flush with the floor 1 so as to form a continuous and unbroken surface therewith. Whenever the use of the cuspidor 4 is desired, 90 the cover 5 may be raised by depressing either of the pedals 13 or 21 accordingly as the one or the other is convenient to the foot. The spring 15 tends to depress the meeting ends of the two levers 10 and 18, 95 and as a consequence to hold the cover 5 in the closed position, as appears in Fig. 1. However, when either of the pedals 13 or 21 are depressed, the spring 15 will be compressed to allow the proper movement of the 100 lever 10 necessary to secure the opening of the cover 5. The depressing of the pedal 13 will swing the lever 10 from the position shown in Fig. 1 to that shown in Fig. 2, which is accompanied by a raising of the 105 link 9, which transmits a corresponding raising movement to the bar 8 and cover 5, swinging the cover up about the hinges 6 to disclose the receptacle 4. The bracket 16 will also cause the companion lever 18 to be 110 rocked in unison, and whenever the other pedal 21 is depressed the lever 18 will swing

the lever 10 in the same way, with similar results.

It will be appreciated from the foregoing that we have provided a simple, cheap and positively operating device for the above described purposes which can be operated from either side of the cover 5, and which conceals the cuspidor when not in use, so as to be particularly useful from a sanitary standpoint, especially in public places such as office buildings and railway cars.

It will be obvious that those skilled in the art may vary the details of construction and arrangements of parts without departing from the spirit of our invention, and therefore we do not wish to be limited to such features except as may be required by the claims.

Having thus described our invention, what we claim as new and desire to secure by Letters Patent of the United States is:

1. In combination with a floor having an opening, of a cuspidor beneath the opening, a cover fitting in the opening and hinged to the floor, a pair of levers, one of said levers made substantially U-shaped and straddling the cuspidor, and means at opposite sides of the cuspidor whereby said levers may be rocked for raising the cover, substantially as described.

2. In combination with a floor having an opening, of a cuspidor beneath the opening,

a cover for the cuspidor hinged to the floor and fitting in the opening, a lever pivoted beneath the floor and having connection at one end to said cover, spring means for normally moving said lever to close said cover, foot-operated means whereby the lever may be rocked to raise the cover, and a second lever having operating means at the other side of the cover and connected to said first-mentioned lever for operating said cover, substantially as described.

3. In combination with a floor having an opening, a cuspidor beneath the opening, a cover hinged to the floor and adapted to fit in the opening, a lever pivoted beneath the floor at one side of the cuspidor, a link connection between said lever and cover, a spring for moving said lever to close the cover, a pedal attached to said lever extending above the floor whereby the lever may be operated to open the cover, a second lever fulcrumed at the opposite side of said cuspidor, said last mentioned lever being substantially U-shaped and straddling the cuspidor, a brace carried by the first-mentioned lever for attaching the second mentioned lever thereto, and a pedal attached to said second mentioned lever and extending above the floor at the opposite side of the cover, substantially as described.

FREDERICK GLASS.
JOHN GLASS.
